UNITED STATES PATENT OFFICE.

FREDERICK HYMANS, OF GLEN RIDGE, NEW JERSEY, ASSIGNOR TO OTIS ELEVATOR COMPANY, OF JERSEY CITY, NEW JERSEY, A CORPORATION OF NEW JERSEY.

SAFETY DEVICE.

1,225,962.

Specification of Letters Patent.

Patented May 15, 1917.

Application filed October 20, 1914. Serial No. 867,589.

To all whom it may concern:

Be it known that I, FREDERICK HYMANS, a citizen of the Netherlands, residing in Glen Ridge, in the county of Essex and State of New Jersey have invented a new and useful Improvement in Safety Devices, of which the following is a specification.

My invention relates to safety devices for elevators and more particularly to that type of safety device or brake in which gripping jaws carried by the car or counterweight or both are adapted to grip stationary vertical guide rails or their equivalent in the hatchway.

One of the objects of the invention is to provide electro-mechanical apparatus of an improved type whereby the gripping jaws may be applied either automatically by means of an electrical governor or manually by means of a switch in the car, said apparatus furthermore being arranged to release the gripping jaws and maintain the same in an inoperative position.

Another feature of the invention resides in the means for controlling the electro-mechanical apparatus.

Other objects of the invention will appear hereinafter, the novel combinations of elements and arrangement of parts being set forth in the appended claims.

Referring to the accompanying drawings, Figure 1 illustrates diagrammatically an elevator car with my invention applied thereto, together with governor mechanism; and a system of electrical circuits; Fig. 2, shows partly in section, a plan view of the safety plank shown in elevation in Fig. 1, together with my improved electro-mechanical apparatus and a system of electrical circuits therefor.

In Fig. 1 is shown an elevator car C, beneath the floor of which is suitably mounted my improved safety device P. Clamps pivoted at 1, 1, and comprising clamping jaws, 2, 2, and 3, 3, are adapted to engage the stationary guides or T-rails, 4, 4, and thus effect a stopping of the car. A coil spring 5 is adapted to actuate both sets of gripping jaws to engage the guide rails through the connections comprising a lever 6 pivoted at 7, and additional link connections 8, 8. Now in the way of controlling the application of the gripping jaws as well as effecting the release of the same from the guide rails, I have provided electro-mechanical appara-

tus of an improved construction which is designated by the reference letter A. This device in its entirety is carried by the safety plank and secured thereto in a suitable manner. This device comprises a pilot motor M which is connected through the intermediary of connection B with the lever 6. The connections B comprise a worm wheel 9, arranged loose on a shaft 10, and provided with projecting pins 9', arranged to engage a trip device or stop pin 11. The pin 11 is held out the path of movement of the pins 91, by means of a spring 12, and is operated into position to be engaged by the said pins by means of an electromagnet 13, through the intermediary of the pivoted lever 14. A worm shaft 15, carrying a worm 15' is arranged to be moved axially from the normal position as shown, to the left. This result may be accomplished in numerous different ways, of which one consists in providing the shaft 15 with a square shank 16 on its right end, which shank fits a hub 17 of a spur gear 18. An additional spur gear 19, forms a driving connection between the pilot motor and the gear 18. The gear 18 is rotatably mounted in a suitable standard such as 19', and the shaft 15, at its left end is suitably supported by a standard 20. It will now be seen that this arrangement permits imparting to the worm shaft a rotary motion and simultaneously an axial motion in the direction of the arrow. The lever 6 is operatively connected with the worm shaft 15 by means of a connection per-

mits imparting to the worm shaft a rotary motion and simultaneously an axial motion in the direction of the arrow. The lever 6 is operatively connected with the worm shaft 15 by means of a connection per-

mits imparting to the worm shaft a rotary motion and simultaneously an axial motion in the direction of the arrow. The lever 6 is operatively connected with the worm shaft 15 by means of a connection per-

ated to open position as illustrated in the drawing, effects the application of the gripping jaws to the guide rails. The parts as illustrated in the drawings are in relative 5 positions attained with the gripping jaws in engagement with the guide rails, such operation in this case being effected by opening the said switch E, although such operation is also controlled by the switch S 10 which is controlled by the governor G. Now in order to effect a release of the gripping jaws from the guide rails, the switch E is closed, thus connecting the pilot motor and winding of the electromagnet 13 with 15 the supply circuit. The circuit for the pilot motor is as follows: from the + conductor, through the governor switch contacts 26, 26, conductor 29, through safety switch E, conductor 30, through switch D, conductor 31, 20 to pilot motor, and from thence to the - line, by way of conductor 32. The circuit for the winding of the electromagnet is by way of the governor switch contacts and the safety switch, and from the junction 30' is 25 connected in a parallel circuit with the pilot motor. The pilot motor now receiving current will effect a rotation of the worm shaft 15 in a clockwise direction, we will say for example, looking from the right on the 30 drawing. The worm wheel 9 being free to turn will thus be rotated in a counter-clockwise direction as indicated by the arrow, until one of the pins 9' comes into engagement with the stop pin 11, which has been 35 actuated into engaging position by means of the electromagnet 13. The worm wheel 9 being held fixed against rotation by the pin 11, results in a movement of the worm shaft and worm axially in the direction of 40 the arrow, thereby actuating the lever 6 to effect the releasing of the gripping jaws from the guide rails. Now when the jaws are fully released, the arm 6' on the lever 6 opens the switch D, thus cutting off the 45 current supply to the pilot motor, which will now come to rest. It will be noted that the electromagnet still receives current and thus maintains the pin in engaging position to hold the shaft 15 against return movement by 50 the action of the spring 5, thus maintaining the gripping jaws in their releasing position, until the circuit for the winding of the electromagnet 13 is opened either by means of the governor or the safety switch E. Now 55 in case the speed of the elevator car exceeds a predetermined limit, the governor G actuates the switch S and separates the contacts 26, thus opening the circuit for the winding of the electromagnet 13. The 60 electromagnet 13 now being deenergized permits the spring to actuate the pin 11 out of engaging position, relatively with the pin 9'. The spring 5 now forces the gripping jaws into engagement with the guide 65 rails thus effecting a stopping of the car.

It will be noted that a quick initial application of the gripping jaws is effected, since the only resistance offered to the spring 5 is that of returning the worm 15' from its extreme left hand position to its position as 70 shown in the drawing. The switch S is locked in an open position by means of the latch 27, thus the releasing of the gripping jaws is prevented, until the latch is released manually. 75

It will now be seen that with my improved arrangement the application of the gripping jaws will be effected either automatically in case of excess car speed, or may be controlled manually from the elevator car. 80 It will be noted that the present safety device differs from other electrically controlled safety devices, in that the same is not put in operation every time the elevator car is stopped at the different floors, but 85 is held in released position and put in operation either automatically in case of excessive speed or manually by means of the safety switch in the car. Furthermore the safety device is put in operation at least twice daily 90 irrespective of the above noted instances, such operations thereof being effected at the close of elevator service at night, by opening the main line switch, and also again in the morning when the elevator is put in service 95 by closing the main line switch. This operation of the safety device twice daily, keeps the movable parts in good working order, and guards against such parts becoming inoperative by being rusted, etc. 100

Although I show my invention applied to a direct current system, the same is equally applicable for alternating current systems. Furthermore I wish not to be limited to the precise details of construction and arrangement of parts as herein shown and described, since various modifications may obviously be made by those skilled in the art without departing from the spirit and scope of my invention. 105

What I claim as new and desire to secure by Letters Patent of the United States is:—

1. In an elevator, the combination with an elevator car, a spring operated car brake, an electrical switch actuating speed governor, electro-mechanical apparatus controlled thereby for controlling the application of the brake, and means for maintaining the said electrical switch in open position when the car speed is excessive. 115

2. In an elevator, the combination with an elevator car, a car brake, means for applying the brake, electro-mechanical apparatus operatively associated with the car brake, a governor, and means comprising a switch and circuits controlled thereby for effecting the application of the brake by the aforesaid means, and for effecting the release thereof by means of the electro-mechanical apparatus. 125

3. In an elevator, the combination with an elevator car, a car brake comprising brake members carried by the car and coöperating guide rails, a spring for applying the brake, 55 electro-mechanical apparatus for releasing the brake members and maintaining the same in released position, a speed governor, and means comprising an electric switch and a system of electrical circuits for effecting the application of the brake members by means of the spring when the car speed is excessive.

10 4. In an elevator, the combination with an elevator car, a car brake, a spring for applying the brake, and means comprising a rotary electric motor and mechanical connections for effecting the release of the 60 brake.

15 5. In an elevator, the combination with an elevator car, a car brake comprising members carried by the car and coöperating guide rails, means for applying the brake, and means for releasing the brake members carried by the car, the said means comprising a rotary electric motor and power transmitting connections between the said motor and the brake members carried by the car.

20 6. In an elevator, the combination with an elevator car, a guide rail, a device carried by the car adapted to grip the rail, a spring arranged to cause the said device to grip the rail, and means for releasing the gripping device, the said means comprising a rotary electric motor and power transmitting connections between the motor and the gripping device, said connections being arranged to permit the application of the gripping jaws by the spring without transmitting motion to the said rotary motor.

25 7. In an elevator, the combination with an elevator car, a car brake, comprising members carried by the car and coöperating guide members, a spring for applying the brake, means comprising a rotary electric motor and power transmitting connections between the motor and brake members for releasing the brake members, and an electrically operated trip device for holding the brake members inoperative.

30 8. In an elevator, the combination with an elevator car, guide rails, a device carried by the car adapted to grip the rails, means for

operating the said device to grip the rails, an electrical governor, and means controlled thereby for effecting the said operation of 55 the gripping device, and electro-mechanical means for releasing and maintaining the same inoperative.

9. In an elevator, the combination with an elevator car, guide rails, a device carried by 60 the car and adapted to grip the rails, a spring for operating the gripping device, a governor, an electric switch operatively associated therewith, and a rotary electric motor and connections between the motor and 65 gripping device, said connections being arranged to permit the operation of the gripping device by means of the spring and without transmitting motion to the rotary motor, and being arranged to effect the release of the gripping device by means of the 70 rotary motor.

10. In an elevator, the combination with an elevator car, a car brake, means for applying the brake, a governor, an electric 75 switch operatively associated therewith, means comprising a rotary electric motor and power transmitting connections between the motor and brake for operating the brake to an inoperative position, an electrically 80 operated trip device controlled by the said governor for holding the brake in said inoperative position.

11. In an elevator, the combination with a car, a car brake, means for operating the 85 brake, means comprising a rotary electric motor and connections between the latter and said brake for operating the latter to an inoperative position, a trip device for holding the brake in said inoperative position, 90 electromagnetic means for operating the trip device, and means for controlling the operation of the said electromagnetic means either automatically by means of a switch operating governor, or manually by means of a 95 switch in the car.

In testimony whereof I have signed my name to this specification in the presence of two subscribing witnesses.

FREDERICK HYMANS.
